Primary Examiner — Charles A Rademaker*Assistant Examiner* — Dana L Sipos(74) *Attorney, Agent, or Firm* — Hasse & Nesbitt LLC; Donald E. Hasse**CLAIM**

I claim the ornamental design for a bottle, as shown and described.

DESCRIPTION

FIG. 1 is a top perspective view of the bottle;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings are for illustrative purposes only and form no part of the claimed design.
